UNITED STATES PATENT OFFICE.

HOWELL D. PRATT, OF PHILADELPHIA, PENNSYLVANIA, ASSIGNOR TO LINK-BELT COMPANY, OF CHICAGO, ILLINOIS, A CORPORATION OF ILLINOIS.

FEEDING MECHANISM FOR CONVEYERS.

1,023,036.

Specification of Letters Patent.

Patented Apr. 9, 1912.

Application filed July 7, 1911. Serial No. 637,310.

To all whom it may concern:

Be it known that I, HOWELL D. PRATT, a citizen of the United States, residing in Philadelphia, Pennsylvania, have invented 5 certain Improvements in Feeding Mechanism for Conveyers, of which the following is a specification.

The object of my invention is to provide a simple and effective mechanism for feeding paper, packages, boxes, or similar material to elevators or conveyers.

The invention is especially applicable to feeding newspapers or magazines to conveyers.

15 By my invention the elevator can run continuously and the carriers can be loaded with papers, or other material, automatically, by the movement of a lever after the papers have been placed on a suitable feeding table.

In the accompanying drawings:—Figure 1, is a side view of my improved feeding device for conveyers; Fig. 2, is a plan view; Fig. 3, is an end view, looking in the direction of the arrow 3, Fig. 2; Fig. 4, is a sectional plan view on the line 4—4, Fig. 1; Fig. 5, is a perspective view of the reciprocating feeding table; Fig. 6, is a sectional view on the line 6—6, Fig. 3; and Fig. 7, 30 is a view of a modification of a detail.

A is an elevator having two chains a , a , in the present instance diagonally arranged, and secured to the chains at intervals are the carriers B having two sides b , b and one end b' ; the carriers being open at one side to receive the material to be conveyed. The bottom of each carrier consists of three slats b^2 , b^2 , b^3 ; the central slat b^3 being narrow and shaped so as to allow the carrier to pass 35 when the reciprocating feeding table is projected. Each carrier is connected to the chains by brackets a' , as shown. The carriers are properly spaced apart so that the feeding mechanism can receive a load, deliver it to a carrier and return.

C is a frame having rails c , on which are mounted the wheels d , d of the reciprocating feeding table D. This table is forked at the outer end; the two prongs d' being spaced sufficiently apart to allow them to pass into the spaces between the central slat b^3 and the side slats b^2 of the carrier. This forked portion of the slide carries the bundle of papers, in the present instance, into 50 the path of the conveyer, and the carrier, 55

as it moves upward, lifts the bundle of papers off the table, which is then retracted; the said slide remaining in its retracted position until another bundle of papers has been placed thereon, whereupon the operator 60 again shifts the mechanism to set it in motion.

Projecting upwardly from the sliding table is a stop d^2 , against which the rear of the bundle of papers rests as it is moved 65 forward onto the carrier, and there is a fixed stop c' on the frame C so that all that is necessary is for the operator to place the bundle of papers on the forked portion of the table D against the stop c' and the rear 70 stop d^2 , thus bringing the bundle into proper alignment with the sides of the carrier.

E is the operating shaft, which is actuated through a sprocket wheel and chain; motion being imparted to the chain from one of the chains of the elevator when the said chain is shifted into position. Under normal conditions the chain is out of position so that the reciprocating feeding table will 75 remain in the retracted position.

Secured to the shaft E is a hub F having a lever f pivoted thereto at f' , and the short arm of this lever is in the path of a lug g on the sprocket wheel G and the other arm 80 of the lever is in position to be actuated by an arm h of a bell crank lever H pivoted at h' . The long arm of the lever H is connected by a link to one arm of the trip lever H' which has a roller h^2 at the outer end 85 of its long arm which extends into the path of the carrier B, so that, when there is a bundle of papers on a carrier, before the particular carrier reaches the loading mechanism the operating mechanism for the reciprocating slide is thrown out of gear by the bundle of papers on the carrier striking the roller h^2 on the arm of the trip lever, so that the carrier, with the bundle of 90 papers, will pass the reciprocating slide 95 even if the bundle of papers is on the slide, and the mechanism shifted so that the slide will automatically deliver the bundle to the carrier and the mechanism will not operate until the first empty carrier comes into position.

I is the operating arm, which, in the present instance, is operated by hand, although it may be operated by the foot by connecting it to a suitable treadle. This 110

operating arm is mounted on a shaft I' adapted to bearings in the frame C , and on the inner end of the shaft is an arm i connected by a rod i' to an arm k on a rock shaft K adapted to bearings in the frame C .

An arm k' on this rock shaft is connected by a link n to the swinging arm N pivoted at n' to a bracket C' carried by the frame C .

On the shaft K is a weighted lever K' and pivoted to one arm of this lever is a latch k^2 having a hook k^3 at its outer end which engages the pin m on the lever M , which is pivoted at m' to the frame. This latch is thrown out of engagement with the pin m by a pin m^2 on the lever when it is moved to its extreme position in one direction. The long arm m^3 of the lever M is connected by a rod p to an arm P on the shaft E and this arm P has a counter-weight p' . The arm P is slotted so that the connecting pin for the rod p can be adjusted to properly time the movement of the table to the carrier. It will be understood that the arm P makes a complete revolution

when the lever is thrown into gear and the shaft E turned. The long arm m^3 is extended in the form of a bar m^4 which is rigidly secured in a socket in the arm and is connected to the table by a link q . As the shaft E makes one revolution it turns the lever M on its pivot and a forward and return motion is imparted to the reciprocating table D .

On the lower end of the rocking frame N is a sprocket wheel G' and a chain s passes around the sprocket wheels G and G' . Located at intervals on the chain are projections s' in the form of sockets which, when the rocking frame is moved outward, project in the path of the lugs a^2 on one of the chains a of the elevator A ; motion being thus imparted from the conveyer to the chain s by the engagement of the lug with the projection and the chain s is moved in the direction of the arrow by turning the shaft E a complete revolution, and consequently, imparting a full reciprocating motion to the table D . It will thus be seen that the mechanism is absolutely under the control of the operator, yet the operator cannot actuate the mechanism when a bundle of papers is on the carrier of the elevator.

The operation of the mechanism is as follows:—If it is desired to convey bundles of periodicals from one portion of a building to another, the elevator is so constructed as to extend from one section of a building to another and the mechanism for supplying the elevator with bundles of paper is located at one or more convenient points. The devices for removing the bundles of paper can be located at any number of points desired. If there are two or more feeding devices, then they are so located

and the mechanism so arranged that it will be impossible for one mechanism to operate when the mechanism preceding it has already loaded a carrier. The operator places a bundle of papers on the forked portion 70 of the reciprocating table D , taking care to place them against the fixed guard c' and the rear guard d^2 on the table. The operating handle I is then shifted so as to throw the lower end of the swinging arm N to

toward the elevator, thus bringing one of the projecting sockets s' of the chain s into the path of the lug a^2 on the chain a of the elevator A , and when the lug contacts with the

socket motion is imparted to the chain s 80 and this motion is transmitted through the sprocket wheel G (which is loose on the shaft) to the hub F through the lug g and lever f , and as the arm P is secured to the

shaft E the chain s will turn the arm one 85

full revolution, as the arm P is connected to the arm M , which, in turn is connected to the table D , and a forward motion will be

imparted to the table carrying the bundle of papers from the frame C into the path 90

of the upwardly moving carrier B , and as the slatted bottom of the carrier will pass

the forked portion of the table it will lift

the bundle of papers off the forked portion

of the table and will convey it to any point 95

desired. The mechanism is so timed that as

soon as the bundle of papers is moved from

the forked portion of the table, the table

returns to its normal position and is locked

in this position as the pin m on the arm M 100

engages the hooked portion of the arm k^2

and retracts the lower end of the arm N so

that the projecting socket s' on the chain s

will be clear of a shifting lug a^2 on the

conveyer chain. At the same time the operating

handle I will be returned to its normal

position and the mechanism cannot be set

in motion until the operating handle is

again shifted, when the above described

operation is repeated.

In some instances I may make the pro-

jection s' on the chain s in the form illus-

trated in Fig. 7; the cross bar s^2 being ar-

ranged to be engaged by the lug a^2 and

rollers s^3 being arranged to travel on rails 115

fixed to the frame N .

In some instances I may provide counting

mechanism, as illustrated in Fig. 1, consist-

ing of the ordinary counter W having the

customary recording mechanism therein

and a lever w pivoted at w' and connected

by a rod w^2 to the recording mechanism;

the lever only contacting with the material

when located on the table, so that, as the

table is projected, the material will actuate

the recording mechanism, showing how

many bundles have been transferred to the

conveyer.

I claim:—

1. The combination of a conveyer, car- 130

riers thereon, a frame, a reciprocating table mounted on the said frame and adapted to be moved into the path of the carrier, operating means for traversing the table, a 5 shaft, a sprocket wheel thereon, a rocking frame also having a sprocket wheel, the chain passing around the two sprocket wheels, said shaft being connected to the means for operating the table, and means 10 for shifting the rocking frame, so as to bring the chain in gear with the conveyer to rotate the shaft and to reciprocate the table.

2. The combination of a conveyer, carriers thereon, a frame, a reciprocating table mounted on the frame and adapted to carry bundles of paper or other material into the path of the carriers, a shaft, an arm on the shaft, mechanism connected to the arm and 20 to the table, so that, on the rotation of the shaft, the table will be reciprocated, a sprocket wheel loose on the shaft, a hub fast on the shaft and adapted to be engaged by the sprocket wheel, a swinging frame, a 25 sprocket wheel on the frame, a chain passing around both sprocket wheels, projections on the chain, with lugs on the conveyer arranged to engage the projections on the chain, and means for moving the frame carrying the sprocket wheel toward the conveyer, so that the lug on the conveyer will engage the said chain and rotate the shaft to cause the table to be reciprocated.

3. The combination of a conveyer, carriers thereon having slatted bottoms, a frame, a reciprocating table having a forked portion adapted to extend into the path of the carriers and so arranged as to allow the carriers to pass and remove bundles of papers or other material from the forked table, a shaft, an arm on the shaft, a hub secured to the shaft and having a projecting portion, a sprocket wheel on the shaft and having a lug engaging the projecting portion 40 of the hub, a rocking frame, a sprocket wheel, the chain passing around both sprocket wheels and having one or more projections, a series of lugs on the conveyer, with means for moving the rocking frame 45 so as to bring the projections of the chain into the path of the lugs on the conveyer in order to impart motion to the chain and to the sprocket wheels, which, in turn, rotate the shaft, causing the table to reciprocate.

5. 4. The combination of a conveyer, a series 55 of carriers on the conveyer, a frame, a reciprocating table having a forked portion adapted to extend into the path of the carriers so that the carriers will transfer material from the table, a shaft, an arm on the shaft, a lever, a rod connecting the frame with the said lever, means connecting the said lever with the table, a hub secured to the shaft, a lever pivoted to the hub, a 60 sprocket wheel loose on the shaft and hav-

ing a lug adapted to contact with one arm of the said lever, a rocking frame, a sprocket wheel on the frame, a chain passing around both sprocket wheels and having one or more projections, with lugs on the conveyer which 70 come in contact with the said projections, an operating arm, a shaft upon which the arm is mounted, and a rock shaft connected to the said hand lever shaft and to the rocking frame so that, on the operation of the 75 hand lever, the rocking frame will be thrown into position that its chain will be moved with the conveyer.

5. The combination of a conveyer, carriers thereon, a frame, a reciprocating table 80 mounted thereon and adapted to be moved into the path of the carriers, a shaft, an arm on the shaft, a lever, a rod connecting the shaft with one arm of the lever, and means connecting the said arm with the reciprocating table, a hub on the shaft, a lever pivoted to the hub, a sprocket wheel loose on the shaft and having a lug adapted to engage one arm of the lever, a pivoted frame, a sprocket wheel on the frame, a chain passing 90 around both sprocket wheels, a projection on the chain, a lug on one of the chains of the conveyer arranged to engage the projection on the said sprocket chain, a rock shaft having an arm, a link connecting the 95 said arm with the pivoted frame, a second arm on the rock shaft, an operating handle connected to the loosely mounted arm for moving the frame into and out of operative position, a third arm on the rock shaft having a hooked latch, two pins on the first mentioned lever, one pin engaging the hooked portion of the latch to draw the frame out of operative position, and the second pin adapted to throw the latch out 100 of engagement with the first mentioned pin.

6. The combination in a conveyer consisting of chains and carriers mounted thereon, said carriers having slatted bottoms, a frame at one side of the conveyer, a reciprocating 110 table having a forked portion adapted to extend into the path of the carriers so that the carriers will lift material to be conveyed from the table, a shaft, an arm on the shaft, a three-armed lever, a rod connecting the three-armed lever with the rod on the said shaft, means connecting the long arm of the said lever with the table, a hub secured to the shaft, a lever on the hub, a sprocket wheel loose on the shaft and having 120 a lug adapted to engage one arm of the lever, a trip lever pivotally mounted so as to extend into the path of the carriers and to be actuated by the material carried by the carriers, a bell crank lever connected to the trip lever and arranged to actuate the lever on the hub to throw it out of the path of the lug on the sprocket wheel, a swinging arm, a sprocket wheel thereon, a chain passing 125 around both sprocket wheels, and projec- 130

tions on the chain arranged to be engaged by lugs on the conveyer, with means for operating said swinging frame.

7. The combination of an elevating conveyer, a series of carriers thereon, said carriers having slatted bottoms, a frame at one side, rails on the frame, a table having wheels adapted to travel on the rails, said table being forked at its outer end and adapted to extend into the path of the carriers so that the carriers will remove material placed on the table, a shaft, an arm on the shaft, a three-armed lever, a rod connecting the long arm of said lever with the arm on the shaft, a rod and link connecting said arm to the table, a rock shaft having a hooked arm arranged to engage a pin on one of the arms of the three-armed lever, a pin on the other arm adapted to throw the lever out of engagement with the said first mentioned pin, a rocking frame, a sprocket wheel on the rocking frame, a sprocket wheel

loose on the first mentioned shaft, a chain passing around both sprocket wheels and having projections, lugs on the conveyer arranged to engage the said projections on the chain, an arm on the rock shaft, a link connecting the arm with the rocking frame, a third arm on the rock shaft, an operating hand lever connected with the said arm, a hub secured to the shaft and having means engaged by the sprocket wheel so that, when the sprocket wheel is turned, the shaft will turn with it and reciprocate the table, the table automatically stopping at its normal position, due to the moving of the rocking frame away from the conveyer. 25 30 35

In testimony whereof, I have signed my name to this specification, in the presence of two subscribing witnesses.
